UNITED STATES PATENT OFFICE.

HALLET E. SHEETZ, OF REMINGTON, INDIANA.

DESIGN FOR A COUCH-RACK.

SPECIFICATION forming part of Design No. 34,983, dated August 20, 1901.

Application filed June 20, 1901. Serial No. 65,362. Term of patent 14 years.

To all whom it may concern:

Be it known that I, HALLET E. SHEETZ, a citizen of the United States, residing at Remington, in the county of Jasper and State of Indiana, have invented and produced a certain new and original Design for a Couch-Rack; and I do declare the following to be a full, clear, and exact description of the invention, such as will enable others skilled in the art to which it appertains to make and use the same.

The invention relates to a new and original design for a couch-rack—that is, a device adapted when used in pairs to rest upon the floor and straddle a couch or sofa, so as to support a second couch or sofa above the first; and it consists of a rack of the configuration shown in the accompanying drawings, in which—

Figure 1 is a perspective view, and Fig. 2 is a side elevation.

The leading feature of the design comprises a stand 1, having ornamental base-wings 2, and provided at its ends with parallel bars 3 and 4, projecting in the same direction, and 25 fanciful open-work corner-pieces 5 and 6.

What I claim is—

The design for a couch-rack, as herein shown and described.

In testimony whereof I have hereunto set 30 my hand in presence of two subscribing witnesses.

HALLET E. SHEETZ.
